UNITED STATES PATENT OFFICE.

EDWIN A. LEVERING, OF PHILADELPHIA, PENNSYLVANIA.

DENTAL FLASK.

SPECIFICATION forming part of Letters Patent No. 497,723, dated May 16, 1893.

Application filed March 6, 1893. Serial No. 464,746. (No model.)

To all whom it may concern:

Be it known that I, EDWIN A. LEVERING, a citizen of the United States of America, residing at Philadelphia, in the county of Philadelphia and State of Pennsylvania, have invented certain new and useful Improvements in Dental Flasks, of which the following is a specification, reference being had therein to the accompanying drawings.

My invention relates to improvements in dental flasks, its object being to provide a self closing and locking flask that can be readily closed and securely locked, that will have no projections on its circumference, one whose cap-plate will be strengthened throughout nearly its whole area by the locking device, and one in which the wear on the locking device can be distributed.

The invention will first be described in connection with the accompanying drawings, and then pointed out in the claim.

Figure 1 of the drawings is a perspective view of a flask embodying my improvements. Fig. 2 is a vertical sectional view taken through the lock-rods. Fig. 3 is a perspective view of a wrench used in turning the lock-disk.

Referring to the drawings, A is the lower section of the flask, having an integral bottom plate *a*, and provided with inside vertical tubular projections 1, located opposite each other. Holes for receiving the lower ends of the lock-rods are formed in the bottom plate immediately under the tubular projections.

B is the upper section of the flask, also provided with inner vertical tubular projections 2, arranged to register with those in the lower section when the parts are together.

C is the cap-plate, provided with a central stud or pivot 3; and through this plate, near its outer edge, are formed two diametrically opposite holes 4, of the same diameter as that of the tubular projections in the upper and lower sections.

D are lock-rods, loosely fitted within the tubular projections of the lower section A, their lower ends being screw-threaded and passed through the bottom plate *a*, and held in place by nuts 5. The upper ends of these rods are recessed in one side, as at 6, for a purpose hereinafter explained.

E is the lock-disk, whose diameter is but

slightly less than that of the cap-plate. At the periphery of this disk are two integral segmental oppositely-inclined rigid cams 7; and in the edge of the disk, at the small end of each cam, is formed a notch 8, whose diameter is slightly greater than that of the lock-rods D. From the center of the disk, on the upper side, rises an integral hub 9, adapted to fit neatly over the stud or pivot 3 on the cap-plate, so that it may be held in proper relation to that plate and also to the lock-rods. Studs 10 project upward from the top of the lock-disk, they being designed to receive a wrench *w*, such as is shown in Fig. 3, for the purpose of turning said disk. In the meeting edges of the upper and lower sections is formed a pouring spout 11, for use when it is desired to make metal plates.

The manner of assembling the parts and the operation of the locking device will be apparent from the drawings.

It will be noticed that by placing the lock-rods inside of the flask I not only give the latter a smooth outer surface, which is desirable, but I am enabled thereby to make those rods serve to hold the cap-plate in place on the upper section, thereby, through the medium of the stud or pivot and the centering-hub, assuring the proper relation between the segmental cams on the lock-disk and the recesses in the lock-rods. Furthermore by making the lock-plate in the form of a disk nearly covering the cap-plate, I am enabled to make the latter very light without danger of its springing or warping while the flask is in use; and by forming the segmental cams rigid and placing them at the edge of the disk, the pressure in locking is exerted equally over the entire area of the cap-plate. Again, by threading the lower ends of the lock-rods and passing them through the bottom of the flask, I am enabled, by means of the nuts, to adjust the rods vertically to any extent desired without turning the recesses out of the path of the cams, whereby any wear on the recessed portions of the rods or on the upper surface of the cams can be readily compensated, and the rods can be made to engage with any portion of the top surface of the cams, so that the wear on the whole locking device can be distributed.

Having thus described my invention, what I claim as new, and desire to secure by Letters Patent, is—

In a dental flask, the combination, with the upper and lower sections having interior vertical tubular projections, of lock-rods recessed at their upper ends and screw-threaded at their lower ends, said rods located in the tubular projections, their lower ends passed through the bottom plate of the flask and provided with nuts, a cap-plate through which

the rods project, and a lock-disk having rigid cams on its upper surface arranged to engage with the recesses in the lock-rods, for the purposes set forth. 15

In testimony whereof I affix my signature in presence of two witnesses.

EDWIN A. LEVERING.
